UNITED STATES PATENT OFFICE.

HARRY P. DAVIS, OF PITTSBURGH, AND CHRISTIAN AALBORG, OF WILKINSBURG, PENNSYLVANIA, ASSIGNEES TO WESTINGHOUSE ELECTRIC & MANUFACTURING COMPANY, A CORPORATION OF PENNSYLVANIA.

CIRCUIT-INTERRUPTER.

1,123,255.

Specification of Letters Patent.

Patented Jan. 5, 1915.

Application filed June 25, 1906. Serial No. 323,353.

To all whom it may concern:

Be it known that we, HARRY P. DAVIS and CHRISTIAN AALBORG, citizens of the United States, and residents, respectively, of Pittsburgh and of Wilkinsburg, in the county of Allegheny and State of Pennsylvania, have invented a new and useful Improvement in Circuit-Interrupters, of which the following is a specification.

10 Our invention relates to circuit-breakers and has special reference to such devices as are adapted to automatically interrupt circuits upon the occurrence of predetermined conditions.

15 The object of our invention is to provide a circuit-breaker of the class above indicated, which shall be simple and durable in construction, electrically operated, automatically actuated to interrupt the circuit under 20 predetermined conditions and specially adapted for outdoor service.

In the application of a relatively high voltage trolley line construction to general railway service, it is desirable to divide the 25 trolley line into sections which may be readily disconnected from the source of supply so that repairs may be effected without danger. Circuit interrupters which are employed for this purpose must be amply protected from weather conditions and arranged so that the operating parts may be inspected and repaired without danger of injury to the attendant. In order to accomplish the aforesaid objective results, the circuit 30 breaker of our present invention is entirely inclosed in a water tight casing, is electrically operated and is provided with an automatic tripping mechanism, which may be actuated when the current traversing the 35 circuits completed through the switch exceeds a predetermined amount or when the cover of the inclosing casing is removed or moved to open position. The overload tripping device is so arranged that the electric 40 operating mechanism will not close the switch when the tripping coil is energized.

As is usual in high voltage circuit-breakers, the operating contact members, which are first separated when the circuit is interrupted, are oil-immersed but the stationary members, instead of being directly connected to the line conductors, as is the usual arrangement, are connected to a second set of

stationary members by means of bridging contact switch members that are relatively 55 stationary and are supported by and insulated from the cover. The second set of stationary terminal members are connected to the line conductors and are so embedded in insulation that when the cover is open 60 the exposed contact members are thoroughly protected and are almost inaccessible to an 65 inspector or attendant who may be employed in repairing the operating mechanism.

Our invention is illustrated in the accompanying drawings, in which—

Figure 1 is a view, mainly in elevation but partially in section, of a circuit interrupter constructed in accordance therewith and Fig. 70 2 is a plan view of the interrupter with the cover partially broken away. Fig. 3 is a detail view of the cover handle mechanism, and Figs. 4 and 5 are, respectively, front and side elevations of the operating mechanism shown in Fig. 1. 75

Referring to the drawings, the circuit interrupter illustrated comprises stationary contact members 1, 2, 3 and 4, movable bridging contact members 5, 6 and 7, an inclosing casing 8, having a hinged cover 9, a detachable fluid-containing tank 10, and an operating mechanism 11. The stationary contact members 2 and 4 comprising vertical rods 12 of conducting material, which are 80 attached to and insulated from the bottom of the casing 8 by means of molded insulating supports 13. The lower extremities of the rods 12 project from holes in the bottom of the casing and are provided with terminal members 14, to which line conductors 85 may be attached. These members are protected by bell-shaped insulators 15, which are fitted into the lower extremities of the insulators 13 and form a tapered plug and 90 sleeve connection therewith. The upper extremities of stationary members 2 and 4 are provided with forked projections 16 and 17, which are adapted to be respectively engaged by the bridging contact members 5 95 and 6.

The upper portions of the stationary contact members 1 and 3 are similar to those of the members 2 and 4, being provided with forked terminal members 18 and 19, which 100 are adapted to be engaged by the opposite

extremities of the bridging contact members 5 and 6. The lower extremities of the members 1 and 3 extend through suitable holes in the casing 8, from which they are separated by insulators 29 and are provided with resilient cup-shaped terminal members 21 of a well known construction, such as are shown and described in Patent No. 758,621, granted to Westinghouse Electric & Manufacturing Company, as assignee of Harry P. Davis. The movable contact member 7 that is adapted to engage the stationary resilient members 21, is connected to an operating lever 22 by a link 26 and is located, together with stationary members 21, in the fluid-containing tank 10.

The tank 10 is normally held in position by means of bifurcated projections 23 and supporting bolts 24, the upper extremities of which extend into the casing 8 and are provided with binding nuts 25. By reason of this construction and arrangement of parts, it is impossible for the current-carrying contact parts located in the tank to be uncovered until the cover 9 of the casing has been swung open to entirely disconnect these members from the supply circuits. The upper extremity of the link 26 is pivotally connected to a clamp 27 that is attached to and insulated from the operating lever 22. In this way, the operating mechanism 11 is exempt from any possibility of becoming electrically connected to the supply circuit.

The movable bridging contact members 5 and 6 comprise switch blades which are built up of several strips of conducting material, an intermediate strip being shorter than the others so that a resilient connection may be maintained between the ends of the bridging contact members and the rigid forked terminals of the stationary members. The bridging contact members are relatively stationary, both being mounted upon insulators 28 that are attached to the inside of the cover 9.

The structure thus far described is not claimed herein but constitutes the subject-matter of a divisional application, Serial Number 699,973, filed May 27, 1912.

The cover 9 is provided with a flange 9^a which overhangs the upper edge of the casing 8, so that water is prevented from running into the casing, and it is pivotally mounted upon hinge pins 29, which are supported by forked projections 30 on the outside of the casing. In order to raise and lower the cover, which may be relatively heavy, a handle lever 31 is pivotally mounted upon a stationary shaft 32 that projects from the side of the casing and is connected to the cover 9 by means of a forked projection 33 and a link 34. The arrangement of parts is such that the cover may be swung open through a predetermined angle and se-

curely locked in such position until the handle lever is swung back through a small angle to release it.

The operating mechanism 11, which is mounted upon a stationary frame 35 attached to the casing 8, comprises an operating magnet 36, a bell crank lever 37 and a tripping magnet 38. The operating lever 22 is fulcrumed upon a stationary shaft 39 that is mounted in the frame 35 and at an intermediate point in its length, located between the shaft 39 and the point of connection with the link 26, it is connected to one arm 40 of the lever 37 by a link 41. The lever 37 is fulcrumed upon a stationary shaft 42 and is so arranged that movement of the lever through a predetermined angle in the one or the other direction serves to actuate the operating lever 22 and thereby move the bridging contact member 7 into and out of engagement with the stationary contact members 21. The arm 43 of the lever 37 forms a slightly obtuse angle with the arm 40 and to it is pivotally connected a latch 44. The operating magnet 36 comprises a U-shaped stationary core member 45, upon which magnet coils 46 are mounted and a movable core member 47 to which a magnet yoke 48 is attached. A bifurcated lever 49 is fulcrumed at one end upon the stationary shaft 42 and is provided with a pin 51 having a roller 50 to be engaged by a notch 52 in the lower extremity of the magnet yoke 48 which projects between the two parts of the lever 49. The outer extremity of the lever 49 is provided with a gib 53 which is normally engaged by a notch 54 in the latch 44, so that movement of the lever 49, which is caused by the movable member 47 of the magnet 36, is imparted to the arm 43 of the lever 37. When the movable contact member 7 is in engagement with the stationary contact members 21, the link 41 and the arm 40 of the lever 37 are in substantially the same straight line and the movable member 47 of the electro-magnet is in engagement with the stationary member 45. In order to prevent the interruption of the circuit upon the deenergizing of the operating magnet coils 46, a latch 55 is pivotally mounted upon the stationary shaft 39, within the forked extremity of the lever 22, and is provided with a hook 57 which normally engages the gib 53. The hook of the latch 55 is held in engagement with the gib by means of a spring 58, which acts against an arm 59 of the latch. A third arm 60 of the latch 55 is enlarged at its outer extremity and is adapted to be engaged by a projection 61 on the inside of the cover 9 when the cover is slightly open. The engagement of the projection 61 with the arm 60 serves to rotate the latch through a small angle in opposition to the spring 58 and to disengage the hook 57 from the gib 53. When the gib is re-

leaved, the movable core member 47 of the magnet 36 is permitted to fall to the lower limit of its path of movement and carry with it the levers 49 and 37, thereby permitting the operating lever 22 to turn upon the shaft 39 and cause the circuit to be interrupted.

The tripping magnet 38 is provided with a movable core member 62 to which a looped projection 63 is attached. A bell crank 64 is pivotally mounted upon a stationary shaft 65 and is normally held in a predetermined position by a spring 66. The arm 67 of the bell crank 64 projects into the loop 63 of the core member 62 and the other arm 68 of the bell crank is connected by a link 69 to the latch 44, the arrangement of parts being such that, when the tripping magnet is energized the bell crank is moved, in opposition to spring 66, through a relatively small angle and the latch 44 is moved about its point of connection with the arm 43 of the lever 37, until it is disengaged from the gib 53. In this way, the operating lever 22 is allowed to fall when the tripping magnet is energized for any reason, and the circuit is interrupted, irrespective of the energizing or deenergizing of the operating magnet 36. The latch 55 releases the gib 53 when the main contact members of the interrupter are separated, by reason of the engagement of a projection 73 on the lever 22 with the arm 59 of the latch. The fall of the movable core member 47 is cushioned by means of springs 70 which are attached, at one end, to stationary posts 71 and at the other end to the lever 49. The springs 70 are not essential but are desirable, since the weight of the core member may be considerable. An auxiliary switch 72 is mounted upon the frame 35 and comprises a single pole, double throw switch, the movable switch blade of which is moved from the one position to the other as the movable core member 47 of the operating magnet is raised or lowered. The auxiliary switch may, of course, be located in any convenient position and it may be found desirable to arrange the movable switch blade so that its position will be varied with the operating lever 22 instead of with the core member 47.

The operation of the device is as follows: Assuming that the interrupter is closed, latches 44 and 55 both being in engagement with the gib 53; if the tripping magnet 38 is energized, by reason of an overload or by any predetermined circuit conditions, either manually or automatically produced, the latch 44 will be actuated, as hereinbefore indicated, and the toggle joint formed by the arm 40 of the lever 37 and the link 41 will collapse. This action permits the movable contact members to drop by reason of their weight, thereby interrupting the main circuit of the device. As the operating lever

22 approaches its lowest position, the projection 73 engages arm 59 and moves the latch 55 away from the gib 53. If an attempt is made, at this point, to close the main circuit by energizing the operating magnet 70 winding 46, the movable core member 47 will be held up and no further result will be obtained until the winding is deenergized. The core member 47, the yoke 48 and the lever 49 will then drop and the gib 53 will be 75 engaged by the latch 44. The interrupter may now be closed in the ordinary manner by energizing the magnet winding 46. The auxiliary switch 72 is not essential to the device but may be employed in the usual manner to disconnect the operating magnet winding from its source of supply, when sufficient impetus has been imparted to the movable core member to effect the engagement of the latch 55 with the gib 53, in order 80 to avoid unnecessary loss of energy and heating in the operating coils.

Although I have shown a specific structure, I desire that variations in size, form and arrangement of parts which do not materially change the mode of operation or result shall be included within the scope of my invention, and that only such limitations shall be imposed as are indicated in the appended claims.

We claim as our invention:

1. In a circuit interrupter, the combination with stationary contact members, movable contact members, an inclosing casing therefor, a cover for the casing and an operating electro-magnet, of means for automatically tripping the interrupter to open the circuit under overload conditions and when the cover is opened.

2. In a circuit interrupter, the combination with stationary contact members, movable members, an inclosing casing therefor, a cover for the casing, an operating electro-magnet, and a latch mechanism, of means for energizing the release magnet under 100 predetermined conditions, and mechanical means for releasing the latch mechanism 110 when the cover is opened.

3. In a circuit interrupter, the combination with stationary contact members, movable members, an inclosing casing therefor, a cover for the casing, a tripping magnet, and a latch mechanism, of means for energizing the tripping magnet under predetermined conditions, and mechanical means for 115 tripping the latch mechanism as the cover is opened, and means for preventing the closing of the circuit when the current traversing the tripping magnet exceeds a predetermined amount.

4. In a circuit interrupter, the combination with stationary contact members, movable members, an inclosing casing therefor, a cover for the casing, a tripping magnet, and a latch mechanism, of means for ener- 130

gizing the tripping magnet under predetermined conditions, and mechanical means for tripping the latch mechanism as the cover is opened, coöperating means detachably connected to the movable contact member, and means for separating the two parts under predetermined conditions.

5. In a circuit interrupter, the combination with an inclosing casing having a re-
10 movable cover, stationary and movable contact members, an operating lever, an operating magnet, a gib operatively connected to the magnet, and a latch carried by the lever and engaging the gib, of a relatively stationary latch also engaging the intermediate member, and means dependent upon either the position of the lever or that of the casing cover for withdrawing the stationary latch.

15 6. In a circuit interrupter, the combination with stationary contact members, movable contact members and an inclosing casing therefor, a cover for the casing, an operating electro-magnet, and an operating lever detachably connected to the movable core member of the operating magnet and permanently connected to the movable contact members for gravity-actuation to open-cir-

cuit position, of means for disconnecting the operating lever from the movable core member of the operating magnet to open the circuit under overload conditions and when the cover is opened.

7. In a circuit interrupter, the combination with stationary and movable contact members, an inclosing casing therefor, a cover for the casing, an operating electro-magnet, a movable core member therefor, and an operating lever interposed between the movable contact and magnet members, of a relatively stationary latch for holding the movable core member in its energized position, and means for automatically disconnecting the operating lever from the movable core member under predetermined conditions, and other means for withdrawing the latch, when the cover is opened, to open the circuit.

In testimony whereof, we have hereunto subscribed our names this 11th day of June, 1906.

HARRY P. DAVIS.
CHRISTIAN AALBORG.
